UNITED STATES PATENT OFFICE.

CHARLES H. ROOPEN, OF WALTHAM, MASSACHUSETTS.

ICE-CREEPER.

SPECIFICATION forming part of Letters Patent No. 761,915, dated June 7, 1904.

Application filed June 5, 1903. Serial No. 160,210. (No model.)

To all whom it may concern:

Be it known that I, CHARLES H. ROOPEN, a subject of the Sultan of Turkey, and a resident of Waltham, in the county of Middlesex and State of Massachusetts, have invented a new and useful Improvement in Ice-Creepers, of which the following is a full, clear, and exact description, reference being had to the accompanying drawings, forming a part of this specification, in explaining its nature.

My invention relates to an improvement in ice-creepers.

It consists in a creeper especially designed to be attached to the shank between the heel and sole of the shoe.

The creeper comprises, mainly, two opposing clamp and spur bearing members made of metal and of so simple a formation that they can even be cast, as is the best way of making them, which of course is of economic advantage. The special structure of these members—the way in which they are combined and made adjustable whereby the clamping portions thereof may be made to engage with the edges of the shank of any size shoe, together with the means for obtaining such adjustment of the members and for holding them at any point of adjusted position—are all features within the purpose of my invention and which can best be seen and understood by reference to the drawings forming a part of this specification, wherein—

Figure 1 shows a plan of my improved ice-creeper applied to the shank of the shoe. Fig. 2 shows a longitudinal vertical section thereof.

Referring to the drawings, A and A' represent, respectively, the two opposing clamp and spur bearing members, which combined form the main structure of the ice-creeper. They are made, preferably, of cast metal. When combined, the members are comprised of the respective plate-sections a a' , overlapping one another on the inner side of the shank of the shoe and made slightly curved in order to conform thereto, the opposing clamps a^2 a^2 made to engage with the respective sides of the shoe-shank and the spurs a^3 a^4 , respectively, and it is especially to be noted that the spur a^3 of the member A is made slightly longer than the spur a^4 of the member A', be-

cause the member A, with its plate-section a , overlaps on the inside adjacent to the shank of the shoe, while the member A', with its plate-section a' , laps on the outside, wherefore the spur a^3 , secured to the inside member, is lengthened to accord in relative length with the spur a^4 , secured to the member on the outside and so that both spurs may have an equality of bearing.

The opposing members A A' are connected or joined together in a manner which permits of their overlapping plate-sections a a' sliding by one another, wherefore the members can be laterally adjusted and their opposing clamps made to engage with the edges of the shank of any size shoe. The members are so combined by the lugs a^5 , formed upon the sides at the inner end of the plate-section a , clasped around the edges of the plate-section a' . Such retention is supplemented by turning over the edges of the plate a about the edges of the plate a' , so forming a kind of way in which the plate a' is adapted to slide. The members are kept from being entirely drawn apart by means of a lug a^6 , formed upon the inner end of the plate-section a' of the member A', extending up into a longitudinal slot a^7 , formed in the plate-section a of the member A, and which lug is adapted to run along the way of said slot as the members are drawn apart and to define their extent of movement by drawing against the edge a^8 , forming the end of said slot. The members are adjusted and held adjusted at any point within the limit of their adjustment, whereby their clamping portions may be drawn and held tightly clasped against the side edges of the shoe-shank by means of the thumb or adjusting screw B. This screw is shown extended through a hole a^9 , formed in the spur a^3 of the member A and fastening into a threaded hole a^{10} , formed in the inner end of the plate-section a' of the member A', the said plate-section being formed with a sufficiency of metal stock upon its under side to make such threaded connection. It is obvious that as this screw is turned in one direction or the other the members are either adjusted together and held or maintained at the point to which they are adjusted or the release of the drawing tension of the screw permits of

the members being forced farther apart. Besides the practical utility of this means of obtaining and maintaining the adjustment of the members the accessibility of the thumb-screw 5 is to be noted in the fact that its head comes at the end of the creeper, where it can be conveniently reached to be manipulated.

The advantages of my invention arise from its extreme simplicity, from the ease with 10 which the parts are put into operative combination, from the effective method of obtaining the adjustment and retention of its members, from the efficiency of their operation, and perhaps more essentially from the simple 15 and relatively cheap way in which a very useful article can be manufactured.

Having thus fully described my invention, I claim and desire to secure by Letters Patent of the United States—

- 20 1. In an ice-creeper, the combination with opposing spur and clamp bearing members, a portion of which members lap by one another, of a screw passing through the spur of one of said members and fastening into the end portion of the other member whereby the adjustment of the respective members is obtained.
- 25 2. In an ice-creeper, the combination of two clamp and spur bearing members A and A',

provided with plate-sections overlapping one above the other between the spurs carried by 30 said members, means for holding said members in sliding engagement with one another, and adjusting means carried by one of said members extending through the spur thereof and fastening into the end of the other member, substantially as and for the purposes set forth. 35

3. In an ice-creeper, the combination of two clamp and spur bearing members A and A', provided with plate-sections a , a' , overlapping 40 one above the other between the spurs carried by said members, means for engaging said plate-sections to slide by one another, a lug carried by the end of one plate-section and adapted to extend into a longitudinal slot 45 formed in the other, and a screw B extending through the spur of the member A and fastening with threaded connection into the end of the underlapping plate-section of the member A', substantially as and for the purposes 50 set forth.

CHARLES H. ROOPEN.

In presence of—

J. M. DOLAN,
SAUL SIPPERSTEIN.
